UNITED STATES PATENT OFFICE.

LAURENCE E. TOPHAM, OF SWAMPSMOTT, MASSACHUSETTS, ASSIGNOR TO UNITED SHOE MACHINERY COMPANY, OF PATERSON, NEW JERSEY, A CORPORATION OF NEW JERSEY.

SHUTTLE.

1,131,095.

Specification of Letters Patent.

Patented Mar. 9, 1915.

Application filed May 20, 1912. Serial No. 698,458.

To all whom it may concern:

Be it known that I, LAURENCE E. TOPHAM, a citizen of the United States, residing at Swampscott, in the county of Essex and State of Massachusetts, have invented certain new and useful Improvements in Shuttles; and I do hereby declare the following to be a full, clear, and exact description of the invention, such as will enable others skilled in the art to which it appertains to make and use the same.

The present invention relates to shuttles, and more particularly to the thread tension, and has for its object the improvement of the construction of the thread tension of the shuttle.

With the above object in view, the present invention consists in the shuttle hereinafter described and particularly pointed out in the claims.

In the drawings which illustrate the preferred embodiment of the present invention, Figure 1 is an elevation, taken partly in section, of the shuttle, the loop-taker and its actuating mechanism; Figs. 2 and 3 are sectional views taken on the line 2—2 of Fig. 1 and illustrate the shuttle detent in different positions; Fig. 4 is a plan view of the shuttle; Fig. 5 is a plan view of the shuttle taken partly in section; and Fig. 6 is a sectional view of the shuttle taken on the line 6—6 of Fig. 4.

Referring to the drawings, the loop of thread drawn out by the needle is cast around the shuttle by means of a rotary loop-taker indicated generally by reference numeral 2. The loop-taker comprises an annular body portion 4 and an inwardly directed thread engaging beak 6 which is arranged to take the thread from the needle. The annular body portion 4 has at its lower end an inwardly projecting flange 8 which is engaged in an annular race-way formed between the body of the loop-taker support 10 and a plate 12 secured to the top of the support. The loop-taker makes three revolutions to each reciprocation of the needle and is continuously rotated in timed relation therewith by means of a bevel gear 14 which meshes with bevel gear teeth 16 cut in the periphery of the annular loop-taker body. The needle (not shown) is arranged

to pass upward through the loop-taker and draws down the thread loop which is entered by the beak 6. The loop-taker support 10 is arranged to be oscillated about a pivot 18 by means of a link 20, so that beak 6 will clear the needle during its idle revolutions. The above described parts are substantially the same, and operate in a manner similar to the corresponding parts illustrated and described in my co-pending application for sewing machines, Serial No. 621,286, filed April 15, 1911.

The shuttle, indicated generally by reference numeral 34, is rotatably mounted within the annular loop-taker by means of an inwardly extending annular flange 30 lying in a plane at right angles to the axis of rotation of the loop-taker and received in a race-way 32 cut around the periphery of the shuttle. The shuttle comprises a discoidal one piece shuttle body 36. On the lower face of the shuttle body is a projection 38 in which is cut a slot 40. The sides of the slot 40 are plane and parallel and the bottom is cut on an arc of a circle. A detent is provided for holding the shuttle stationary as the loop-taker rotates. The detent comprises a plate 42 which is a substantially quadrantal sector. The edge of the plate 42 has the same radius of curvature as the bottom of the slot 40. A notch 44, which is somewhat deeper than the slot 40, is cut in the middle of the curved slot-engaging edge of the plate 42 for a purpose hereinafter pointed out. The plate 42 is formed integral with a rock shaft 46 which is journaled in a bushed bearing 48 in the loop-taker support 10. The inner edge of the rock shaft 46 has a laterally extending arm 50 which bears a pin 52. The pin 52 is received in a cam path 54 in the gear wheel 14. The cam path 54 is so timed that the detent plate 42 is oscillated back and forth between the two positions shown in Figs. 2 and 3 respectively, in timed relation to the rotary loop-taker. The loop-taker 2 rotates from left to right as viewed in Figs. 1, 2 and 3. The beak 6 of the loop-taker engages the thread when the loop-taker is passing through the position illustrated in Fig. 1. At this time the detent plate 42 is in the position shown in Fig. 3. The beak 6 travels

first from the left to the right in front of the shuttle and then from right to left behind the shuttle, as viewed in Fig. 3, and spreads the loop of needle thread over the shuttle. The top upper leg of the loop is free to pass over the unobstructed upper face of the shuttle and the lower leg of the loop is drawn into the notch 44 which occupies the position shown in Fig. 3. As the beak 6 continues to travel around, behind the shuttle, as viewed in Figs. 2 and 3, the pin travels into a part of the cam path 54 nearer the axis of the wheel 14 and rocks the detent plate 42 to the left from the position shown in Fig. 3 to the position shown in Fig. 2.

By the time the detent plate 42 has reached the position shown in Fig. 2 and the notch 44 has released the thread, the beak 6 will have traveled completely around the shuttle so that the loop of needle thread can be pulled free from the shuttle and against the work by the take-up of the sewing machine. It will be noted that the detent plate 42 is always in engagement with the slot 40, so that the shuttle is always held against rotation with the loop-taker. The detent is positively oscillated, so that after the lower leg of the thread loop is drawn into the notch 44 the thread is positively carried between the shuttle and detent across the lower face of the shuttle the length of the slot 40.

The discoidal shuttle body 36 is cup-shaped, having a circular open top recess 60 in which the bobbin 62 is rotatably mounted on a central post 64 upon which it is retained in place by a latch 66. The side wall 68 of the shuttle constitutes a substantially circular ring which is broken at one place 40 where is cut in its top a notch 70 which extends nearly to the bottom of the bobbin-receiving recess. At one side of the notch 70 the inner face of the side wall 68 is recessed to receive an arcuate-shaped plate 72. The inner face of the plate 72 forms a part of the side face of the circular bobbin-receiving recess. One end of the plate 72 extends partially across the notch 70 and terminates in a downwardly extending finger 73. The plate 72 is secured to the shuttle body by screws 74 extending through the plate 72 and screw-threaded into the body portion of the shuttle. The side wall of the shuttle behind the plate 72 has a circumferential slot 76 in which is held a thread-tension leaf spring 78. One end of the spring 78 is bent sharply, and is received in an aperture 80 in the plate 72 so that spring 78 cannot move longitudinally in the slot 76. The other end 60 of the spring 78 terminates in a downwardly extending finger 82 which bears against the outer face of the finger 73. The inner face of the finger 82 is hollowed somewhat to form a shallow thread retaining groove for 85 the bobbin thread which it yieldingly presses

against the finger 73. The pressure of the spring finger 82 against the thread may be regulated by means of an adjusting screw 86 which is threaded through the side wall of the shuttle and bears against the middle of 70 the spring 78. When the shuttle is assembled, the spring 78 is placed against the plate 72 with its bent over end engaged in the aperture 80. The plate 72 is then screwed to the side wall of the shuttle where 75 it conceals and protects the spring 78. The thread-tension device of the shuttle can be easily and rapidly threaded. In threading the tension, the operator before he inserts the bobbin holds a short length of the bobbin 80 thread taut, and brings this taut thread down into the notch 70. The thread is then drawn laterally under the lower end of the downwardly extending finger 73. The thread is then pulled up behind the finger 73 85 and is drawn upwardly between the outer face of the finger 73 and the inner face of the thread-tension finger 82, into the thread groove in the finger 82. After the tension is thus threaded, the bobbin can be dropped 90 into place in the shuttle.

While the preferred embodiment of the present invention has been specifically illustrated and described, it is to be understood that the present invention is not limited to 95 the details of construction illustrated and described, but may be embodied in other structures within the scope of the invention as defined by the following claims:—

1. A shuttle having an open-topped bobbin-receiving recess with a notch in the top of its side wall, and having a thread-tension comprising two relatively yielding, downwardly extending fingers at one side of the notch adapted to hold the bobbin thread 100 between them.

2. A shuttle having, in combination, a body having a bobbin-receiving recess, a plate secured to the shuttle body and forming a part of the face of the bobbin-receiving recess, and a thread-tension spring held 110 between the plate and the shuttle body.

3. A shuttle having, in combination, a cup-shaped discoidal body having a substantially circular bobbin-receiving recess 115 with a notch in the top of its side wall, a plate secured to the shuttle body, forming a part of the curved face of the bobbin-receiving recess, and terminating in a downwardly extending finger in proximity to the 120 notch, and a leaf-spring held between the plate and the shuttle body with its end bearing against the finger to yieldingly engage the bobbin thread and form a thread-tension.

4. A shuttle having, in combination, a cup-shaped discoidal body having a substantially circular bobbin-receiving recess with a notch in the top of its side wall, a plate secured to the side wall within the bobbin- 130

receiving recess and terminating in a thread
engaging finger in proximity to the notch,
a leaf-spring held between the plate and the
shuttle body with its end bearing against
5 the finger to yieldingly engage the bobbin
thread and form a thread-tension, and a
screw threaded through the side wall of the

shuttle and bearing against the spring for
adjusting the tension of the spring.
